SAFETY MOUNTING

Delphio J. Bracci, Haverhill, and Jason M. Davidson, Stoneham, Mass., assignors to Western Electric Company, Incorporated, New York, N.Y., a corporation of New York

Filed June 10, 1963, Ser. No. 286,685
5 Claims. (Cl. 227—62)

This invention relates to safety devices for apparatus having reciprocating driving members, and more particularly to mountings for the impact receiving member of such apparatus.

In apparatus such as a rivet setting machine where a power driven reciprocating member strikes an impact receiving member, there is normally a gap between the two members that may be of such a size that an operator may inadvertently place his hand therebetween and thereby incur an injury when the driven member moves downwardly. Reducing the gap by shortening the length of the stroke of the reciprocating member tends to lower the efficiency of the machine by decreasing the force with which the reciprocating member strikes the impact receiving member.

Accordingly, it is an object of this invention to improve the safety of machines having reciprocating drivers without impairing the efficiency of the machines.

Another object of this invention is to provide a movable impact receiving member mounting to limit the distance between the driven reciprocating member and impact receiving member without affecting the active length of stroke of the former.

Other objects, features and a fuller understanding of the invention may be had by referring to the following description and claims taken in conjunction with the accompanying drawing, in which:

FIG. 1 is a partial, side elevation of a rivet setting machine incorporating a safety device embodying the principles of this invention; and

FIG. 2 is a partially cut-away front view of a mounting assembly for use with an impact receiving member on a riveting machine in accordance with the invention.

Referring now to the drawings, FIG. 1 depicts a partial side view of a rivet setting machine. As shown, this machine comprises an impact receiving member which includes an anvil unit 11, and a vertically reciprocating driver 12 disposed above the anvil unit. The driver 12 and anvil unit 11 cooperate to effect the setting of rivets 14 in parts to be fastened together.

As best seen in FIG. 2, the anvil unit 11 comprises a cylindrical member 30 having a pin 32 biased upwardly by a coil spring 31 and protruding a short distance beyond the top portion of the anvil unit. Although any type of anvil unit may be utilized in accordance with the invention, one with a spring-loaded pin is most advantageous for aligning the surfaces of two or more parts to be fastened together.

The driver 12 together with its mounting apparatus shown generally by reference numeral 13 may be reciprocated through the actuation of any suitable driving mechanism (not shown). A supply of rivets (not shown) is maintained in a feed chute 15. This chute is arranged to release a rivet during each cycle of operation into a position between a pair of yieldably mounted jaws 20. The jaws are arranged to hold successive rivets 14 in alignment with the driver 12. In operation, the holding jaws move downwardly with the driver until the rivet 14 contacts the anvil unit 11 whereupon the travel of the jaws ends. As the driver 12 continues forceably downwardly in engagement with the head of the rivet, the yieldably mounted jaws 20 are spread apart to re-

lease the rivet previously held therebetween. The final impact of the driver upon the rivet in contact with the anvil unit 11 thereafter sets the rivet.

In accordance with an aspect of the invention, the anvil unit 11 is mounted on a spring-biased, vertically movable assembly 40. This assembly comprises a mounting body 47 fastened to a rigid support member 22, which, in turn, is supported by a bracket arm 24 affixed to the frame of the machine. Although the body 47 can be of various cross-sectional shapes, a hollow cylindrical tube-like form is preferred. A piston-like plunger 42, which is fastened to the anvil member 30 by means of the mutually engaging threaded sections 33, serves in part as a stop for the anvil coil spring 31.

Plunger 42 is vertically movable within an axial bore 37 of the mounting body 47 and biased upwardly by a coil spring 43. This spring is constructed to be much more resilient than spring 31 for reasons set forth in detail hereinafter. Movement of the piston-like plunger 42 upwardly beyond the top of body 47 is prevented by a retainer-collar stop 41. The length of the downward travel of the plunger 42 is controlled by an adjustable cup-shaped stop 44. An adjustment screw 46 threaded into the lower end of body 47 determines the vertical position of the downward stop 44. The adjustment screw 46 is locked in position by jam nut 45. The coil spring 43 thus presses against the downward stop 44 to exert a force on plunger 42, to which the anvil unit 11 is fastened, upward against the retaining collar 41.

In accordance with the invention, when the pin 32 of the anvil unit is first contacted by the rivet 14, no riveting action takes place. Rather, because of the resiliency of spring 43, the anvil unit 11 moves vertically downward with the plunger 42 until the latter contacts the adjustable stop 44. At that point, the anvil unit functions in accordance with its usual operation as if it had been fixedly located in the latter position. In the embodiment shown, the pin 32 then retracts and the rivet 14 is inserted and flared outwardly at its hollow end to fasten together the particular parts inserted in the machine.

It is thus readily seen that the gap between the anvil unit and the jaws 20 when in their unoperated state, can be limited to the distance determined by the location of the top of the anvil pin 32 in its protruding position. This distance is adjustable to $\frac{3}{8}$ of an inch in the illustrative embodiment, rather than the 2 inch minimum usually required to provide the necessary length of active stroke on conventional riveting machines. Accordingly, through the use of this invention, which considerably lessens the gap between the driver apparatus and anvil unit, injury to the hand of the operator by the driver is prevented without any actual alteration to or impairment of the operation of the machine.

It is to be understood that the above described embodiment is simply illustrative of the application of the principles of the invention. Numerous other arrangements may be readily devised by those skilled in the art which will embody the principles of this invention and fall within the spirit and scope thereof.

60 What is claimed is:

1. In a machine having a reciprocating driving member and an impact receiving means, apparatus for mounting said driving member and said impact receiving means in said machine so as to reduce the space therebetween without reducing the active stroke of the driving member comprising:
  - a body member having a channel therein which is in spaced relationship with said driving member,
  - a plunger mounted for rectilinear motion in said channel,
  - means attached to said body member for restricting the

rectilinear movement of said plunger between two predetermined limits in said channel, spring means mounted in said channel for biasing the plunger toward one of said predetermined limits, means connected to said body member for adjusting the quiescent position of said plunger and said impact receiving means relative to the driving member, said impact receiving means including an anvil, and a spring-loaded rod normally projecting upwardly through the anvil a short distance beyond the upper 10 surface thereof, and

the spring means biasing said plunger being more resilient than said spring biasing the rod of said anvil such that upon the impact of the driving member with the upper end of said anvil rod, the spring-biased plunger is depressed downwardly until it abuts one of said predetermined limits for restricting the rectilinear movement of said plunger whereupon the rod of said anvil is depressed until said driving member impacts the upper portion of said anvil which 20 is rigidly supported against said plunger.

2. In a machine having a reciprocating driver and an associated anvil, apparatus for mounting the anvil so as to reduce the required space between it and the reciprocating driver comprising:

a cylindrical body having interior walls defining a concentric cylindrical channel therein, means for rigidly connecting said cylindrical body to the machine so that the concentric cylindrical channel is in axial alignment with the path of the reciprocating driver,

a piston type support for said anvil mounted for reciprocal slidable contact along said walls of the cylindrical channel,

an upper stop including a collar screwed to the top of the cylindrical body for limiting the upward travel of said piston in the cylindrical channel,

a lower stop including a slidable plug threadedly connected to a screw in the bottom portion of said cylindrical body for limiting the downward travel of the piston in the cylindrical channel, and

a coil spring located between the piston type support and the lower stop for pressing the piston type support against the upper stop.

3. A riveting machine comprising:

driving means, an anvil mounted for movement with respect to the driving means, and supporting means for the anvil including:

a fixed hollow cylinder, a plunger slidably mounted within the cylinder, first spring means mounted in the cylinder below

25

50

the plunger for normally holding the plunger in an upward position, and second spring means mounted above, and in contact with the plunger for normally urging the movable anvil toward the driving means, said second spring means having less resilience than the first spring means so that when the driving means strikes the anvil, first the plunger will retract within the cylinder, and then the anvil will be retracted to effect the riveting operation.

4. Apparatus for mounting a reciprocating driving member and impact receiving means of a riveting machine so as to reduce the space therebetween without reducing the active stroke of the driving member comprising:

a fixed cylinder having a channel therein, a plunger having a cavity at one end thereof mounted for rectilinear motion in said channel, a rod mounted for rectilinear motion in said plunger cavity, said rod being in spaced relationship with said driving member,

first resilient means mounted in said cavity for biasing said rod toward the driving member, stop means mounted in the fixed cylinder for limiting the movement of the plunger away from said driving member, and

second resilient means mounted between the stop means and the plunger for biasing the plunger toward the driving member, the second resilient means having greater elasticity than the first resilient means so that when the driving member strikes the rod, the plunger will retract in the channel until it abuts the stop member, whereupon further movement of the driving member will depress the rod in said cavity, the riveting operation being effected at the end thereof.

5. Mounting apparatus according to claim 4 wherein: said stop means is threadedly mounted in said channel so as to be rectilinearly adjustable therein to thereby adjust the stroke of said plunger, and

a collar is threadedly mounted on said fixed cylinder to limit the movement of the plunger toward the driving member.
